MEANS FOR PRODUCING HOLLOW BILLETS
FOR HOLLOW DRILLS AND THE LIKEClaes Joel Gejrot, Bofors, Sweden, assignor to
Aktiebolaget Bofors, Bofors, Sweden, a limited
company of SwedenApplication July 23, 1934, Serial No. 736,584
In Sweden July 29, 1933

5 Claims. (Cl. 22—121)

The present invention relates to the manufacture and production of hollow bars or other tubular or hollow bodies, such as hollow ingots for hollow drills and the like, and may be regarded as an improvement of the invention disclosed in my copending application, Serial No. 697,987, filed November 14, 1933.

As described in my above identified application such hollow bodies are produced by casting molten metal from below around an insert or tube inserted into a mould, which is provided with a discard head box arranged in the upper part of the mould. In said method the casting is carried out, either in small moulds having only one mould chamber or, preferably, in moulds containing a plurality of mould chambers, below connected with a common inlet channel for the molten metal, each of said mould chambers being provided with a discard head box arranged in the upper part of the mould chamber around the tube inserted therein.

According to the preferred embodiment of the invention disclosed in my above-mentioned application, said discard head box is given such a shape that it, with the exception of a hole for the tube as well as necessary vent openings arranged therein, closes the mould or mould chamber at the top. The top end of the tube extending through said hole at the top of the discard head box is secured in place by means of a cover placed on the mould, said cover having a hole which receives the upper end of said tube, and vent openings between the walls of said hole and said tube. In other respects the features of the method and means set forth in my prior application may not be described for the purpose of avoiding repeating.

In the embodiment of my prior invention described above, the core, as will be seen from the foregoing, extends through the whole discard head. Consequently, that part of the core which is located within the discard head will be removed with the latter and be lost. This, however, is a great disadvantage, especially if the core material is expensive, as is often the case, for instance in the production of hollow billets for hollow drill steel, where use is made of a tubular core of stainless steel.

The object of the present invention is to obviate said disadvantage and save expensive material by providing means whereby it becomes possible to carry out such a casting operation in a mould provided with a discard head box, without having the core or insert tube enter or project into or through the whole of the discard

head, yet ensuring that the desired position of the core or insert tube is maintained, in the centre of the mould or otherwise.

For that purpose, according to this invention, the core or insert tube is arranged in such a way that it ends below the top of the discard head box arranged in the upper part of the mould or mould chamber, and the top end of the tube is secured in place by means of a centering member arranged in the upper part of said mould or mould chamber. For convenience, the term "centering" is used to designate the securing in place of the tube, whether this be in the centre of the mould chamber or otherwise.

According to a preferred mode of carrying out this invention, the tube is arranged in such a way that it extends slightly into the lower part of the discard head box, where the centering of the top end of the core is effected by means of a centering member inserted into or embracing the tube or arranged on top of the tube.

In the accompanying drawing the new means for carrying out the method of manufacture of hollow bodies according to the invention are illustrated by way of example.

Fig. 1 is an elevation, partly in vertical section, of a mould containing a plurality of mould chambers, only one of which is shown in section, said mould chamber being in the upper part provided with a discard head box and a centering member for the tube inserted therein.

Fig. 2 is a section on a larger scale through the upper part of Fig. 1 taken on the line II—II in Fig. 1.

Fig. 3 shows a section through the upper part of a mould where the discard head box itself serves as the centering member.

Fig. 4 shows another embodiment of the centering member and

Fig. 5 is a section on the line V—V of Fig. 4. Referring to Figs. 1 and 2, I designate the mould, in which a plurality of mould chambers 10, in this case five, are arranged. The bottom of the mould consists of receptacles, or runner bricks, 11 of refractory material arranged closely together, one plate for each mould chamber, said runner bricks being provided with a central channel 12 forming an intake channel for the molten cast metal and common to the whole mould. One end of the channel 12 communicates with a box 13 provided with a common inlet opening 14 for the molten metal, whereas the opposite end of the channel is plugged. From the channel 12 two inlet openings 15 lead to each of the mould chambers 55

above the runner bricks 11. On the top sides of the runner bricks 11 there are provided recesses 16 for centering the lower end of the tubes inserted into the mould chambers.

- 5 At the upper end each mould chamber is provided with an enlargement 2 in the inside wall of the mould chamber, the bottom of said enlargement being defined by a shoulder 3 in the mould wall. In said upper part of the mould 10 chamber there is inserted a thin plate 4 serving as a discard head box. As shown in Fig. 2, said plate 4 at the lower end is provided with outwardly bent (or welded thereto) strips 5 bearing against the shoulder 3, the lower edge of 15 the plate projecting into the mould below the shoulder 3, as indicated by numeral 6 in Figure 2. Towards the top, the plate 4 is contracted to form a box, which at the top is provided with an opening or a hole for the upper end of the 20 centering member 8 arranged on top of the tubular core 7 inserted into the mould chamber and extending slightly into the lower part of the discard head box. The mould also is provided with a cover 9 with handles 19, said cover having a 25 hole 17, which receives the upper end of said centering member 8 and secures it in place. Said cover also is provided with vent openings 18, corresponding vent openings being arranged at the edges of the hole in said plate 4. The 30 top part of the plate preferably is so dimensioned, that when the cover 9 is not put in place, the plate projects somewhat above the top surface of the mould and so that when said cover is put in place on the mould, the plate will be 35 pressed down to bear against the sides of the centering member 8.

Before putting the cover in place, the space around the discard head box is filled with sand, asbestos or some other suitable insulating material.

40 In the above described example the centering member 8 consists of a tube constituting an extension of the tube proper 7 of expensive material, which tube extension is made of a cheaper material, for instance mild steel or common commercial steel or refractory material. Said tube extension may either be united to the tube proper, if of metal, for instance by spot welding, or, where the tube consists of a tube with 45 another core 22 inserted in it, as also shown in the figures, be loosely put on top of the expensive tube, the inserted core extending through both parts of the tube. If it is desired to use 50 an inserted core, which does not extend to the bottom of the mould, the top end of said core may be provided with a flange or collar (not shown) adapted to bear against the top end of said tube extension 8.

55 In case of using a tubular insert with a core 60 inserted therein, the tube extension 8 also may be dispensed with, provided that the projecting part of said inserted core 22, as shown in the figures, projects sufficiently from the upper end of the tubular insert to permit the centering of 65 said tubular insert. In such a case, the projecting part of the inserted core serving as a centering member suitably may be covered with graphite, clay or other suitable material in order to prevent the molten metal from welding to 70 the same. Further, said projecting part may be provided with flanges or collars (not shown) for keeping said inserted core, axially or radially, in the right position. In all the above-mentioned cases, where use is made of a tubular in-

sert with a core inserted therein, the latter, instead of being tubular, also may be solid.

Referring to Figures 3 to 5, said figures show moulds having only one mould chamber. It is, however, evident that the arrangement shown 5 in said figures also may be used in moulds having a plurality of mould chambers.

According to the modification shown in Fig. 3 the centering member for the core constitutes a part of the discard head box 4a itself. Thus, 10 the central part of said discard head box is given a downwards projecting form 8a, which enters the top end of the insert tube 7 and serves as a centering member for the same. By giving this centering member a tapered form it will be possible to vary the diameter of the insert without altering the discard head box, by merely varying the length of the insert. The plate 4a, which at the top is provided with the vent opening 20, may be made of sheet iron or sheet steel, preferably corrugated or provided with undulations in order to make it stiffer and more resistant. Also, for the same purpose, the space 21 between the walls of the part 8a of the discard head box may be filled and packed with sand, asbestos or 25 fire proof materials, which at the same time serve as heat-insulating materials. Obviously, instead of the discard head box being made of sheet iron or sheet steel, it may be made of refractory material, in which case the use of special insulating material may be dispensed with.

30 In Figures 4 and 5 the centering member consists of a cross-piece 8b in the centre provided with a hole for the insert 7, and with its arms 23 bearing against the walls of the mould or the 35 discard head box 4b. In this case, the top end of the insert, if tubular, must be plugged or otherwise closed for preventing molten metal to flow into the tube.

40 In Figures 3 and 4 the lower ends of the discard head boxes are shown as bearing against the shoulders 3, but the same may also be shaped with projecting parts and strips as indicated by numerals 6 and 5 in Fig. 2. Further, the moulds also may be provided with covers.

45 It is understood that the invention is not limited to the precise details of construction and arrangement herein set forth, as it is obvious that various modifications may be made therein without departing from the spirit of the invention.

50 Having now particularly described the nature of my invention and the manner of its operation, what I claim is:

1. Means for casting tubular bodies comprising, in combination, a mould having inlet openings at its bottom, a heat insulated discard head box made of sheet metal arranged in the upper part of the mould chamber, a tube inserted into said mould with its upper end extending slightly 60 into the lower part of said discard head box, means for positioning the lower end of said tube at the bottom of said mould chamber, a centering member for the top end of said tube arranged on top of the tube and constituting an extension of 65 cheaper material of the tube proper, said discard head box being tapered upwards towards its top and arranged to bear, at its bottom against the walls of said mould chamber and with its upper end against said tube extensions which 70 box, with the exception of vent openings arranged therein, closes the mould at the top.

2. Means as claimed in claim 1, characterized 75 therein that said tube extension is united with the top end of the tube proper.

3. Means as claimed in claim 1, characterized therein that said tube extension is loosely put on top of the tube proper by means of a core inserted into and extending through both parts 5 of the tube.

4. Means as claimed in claim 1, characterized therein that the top end of said tube extension is secured in place at the top of the discard head box by means of a cover placed on the 10 mould and provided with a hole which receives the top end of said tube extension.

5. Means for casting hollow bodies comprising, in combination, a mould having inlet openings at its bottom, a discard head box arranged in the

upper part of the mould chamber, which box, with the exception of necessary vent openings arranged therein, closes the mould chamber at the top, a tube inserted into said mould with its upper end extending slightly into the lower part of said discard head box, means for positioning the lower end of said tube at the bottom of said mould chamber and a centering member for the top end of said tube consisting of a cross-piece arranged in the lower part of said discard 10 head box, in the center provided with a hole, which receives said tube and with its arms bearing against the walls of the mould chamber.

CLAES JOEL GEJROT.
